UNITED STATES PATENT OFFICE.

JOHN B. NEIL, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,510, dated October 4, 1881.

Application filed July 29, 1881. Term of patent 3½ years.

To all whom it may concern :

Be it known that I, JOHN B. NEIL, of New York, in the county and State of New York, have invented a new and original Design for 5 Carpets, of which the following is a specification.

This invention relates to a new and original design for carpets and similar fabrics, and consists in the novel grouping and configuration 10 of figures hereinafter more fully described.

The accompanying photograph illustrates a face view of a carpet having my new design.

Figure A is a bouquet of roses with rose-leaves projecting upward and downward therefrom. From this figure also project moss-like 15 branches and some star-shaped flowers. A bent line or bar connects figure A with the figure F, which is a bunch of leaves with some star-shaped flowers projecting downwardly 20 therefrom toward the left. Another bent line or bar joins the figure A with the figure E below, which is also a bouquet of roses with rose-leaves and moss-like ferns, the leaves being most prominent in this bouquet. From the bar 25 or bent line that joins the figures A and E projects diagonally downward another bar, which is doubled into a square at the lower portion and there turned up again, and which holds in the square the group c, which is composed of 30 two full-blown roses with appropriate leaves, and also the twig e, as shown. From the said square a bar extends sidewise to a figure, D, which is likewise a bouquet, containing one full-blown rose with appropriate rose-leaves, 35 and which figure, by star-shaped flowers, connects with the figure c, as shown. From the figure D the bar which seems to traverse the entire carpet bends up, forms another square, to the right of which, when the carpet is

matched, is a peculiar zigzag formation, (marked 40 b,) which is directly above the figure A, and from which, by further angular bends, the bar extends to the figure F, that has already been described. In the lower part of the zigzag formation b is a spray, f, that extends upward 45 from the figure A, as shown in the upper left-hand corner of the photograph. B is a further bouquet of roses, having flowers at its lower and the leaves at its upper part, the leaves being mostly rose-leaves, excepting a pinnate 50 leaf that projects upward toward the figure E. From the top of the figure B extends also a branch of the above-mentioned bar or line that is bent into a fantastic form, d, and extends thence nearly to the figure E, as shown. From 55 the figure F the above-mentioned bar or stripe extends also to the right, and is there doubled into a system of three rectangles, as shown at a, and thence carried down into contact with the figure c. Above the figure a is the figure 60 G, which is placed in the bend of the same bar that connects the figure B with the figure A. The group G is a branch of a rose-shrub, having a well-defined stem at the lower part with rose-leaves thereon, and two full-blown roses at 65 the upper part.

This carpet derives its peculiar appearance from the grouping of the floral decorations, and also from the traversing bar that forms the fantastic shapes which are shown in the photograph. 70

I claim—

The design for carpets, consisting of the figures A B D E F G c e, and of the bar forming the figures a, b, and d, substantially as shown. 75
